Application December 31, 1941, Serial No. 425,019

14 Claims. (Cl. 101—247)

This invention relates to sheet printing machines and more particularly to improved means for controlling cylinder tripping mechanism of a rotary sheet fed printing machine.

The present invention is especially adapted for use in a printing machine for printing or decorating sheets of relatively heavy paper, cardboard, tin plate or analogous materials, with which suitable mechanism is provided to feed the sheets one at a time and in timed relation to the co-operating printing cylinder, and wherein suitable mechanism is also provided to trip or separate one of the printing cylinders away from the other. When sheets are fed to printing cylinders, it is desirable that, should the feeding mechanism fail to feed a sheet properly and it is presented to the printing cylinders either before or later than the proper time, such condition will be detected and the cylinders be tripped "off impression" to avoid damage and inconvenience. It is also desirable that, when a sheet is presented either in advance of or behind its proper feeding time, the machine be stopped to permit removal of the improperly fed sheet and prevent damage to the machine.

One object of this invention is to provide in a printing machine of the kind mentioned, an improved control device for a cylinder tripping mechanism adapted to be actuated when one sheet of a series advancing toward the cylinders along a feed guide is absent from a particular place on the guide at a time when it should be present, or is present at that place at an improper time.

Another object is to provide in a control device of the kind mentioned, means adapted to be engaged by an advancing sheet to detect its timed relation and effect a device to control a cylinder tripping mechanism to prevent tripping of the cylinders when the sheet is moving "in time," and to cause tripping of the cylinders when a sheet is not moving "in time" and to stop the machine.

It is also an object of this invention to provide a trip control device of generally improved construction, whereby the same will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein dis-

closed may be made within the scope of what is claimed without departing from the spirit of the invention.

A preferred embodiment of the invention is illustrated in the accompanying drawings, wherein:

10 Figure 1 is a fragmental side view of the co-operating printing cylinders of a printing machine, the tripping mechanism therefor, and the control device for the tripping mechanism and which embodies the features and principles of this invention, the several parts being illustrated in their relative positions while the machine is in operation and a sheet is being printed;

15 Figure 2 is a fragmental side view of the co-operating printing cylinders and the tripping mechanism in their positions when the mechanism is actuated to trip the impression cylinder away from the plate cylinder, for instance, when 20 a sheet is absent from the series of sheets being fed to the cylinders;

25 Figure 3 is a fragmental side view of the control device for the cylinder tripping mechanism with the parts thereof in position to set the tripping mechanism to trip the impression cylinder "off" and to also stop the machine; and

Figure 4 is a diagram of an electrical control circuit for the control device herein illustrated.

In Figure 1 of the drawings, a sheet S1 is shown 30 passing between a plate cylinder 11 and an impression cylinder 12 to be printed. Another sheet S2 is shown being fed toward the cylinders along a sheet feed guide 13 by propelling rollers 14 and 15, disposed below a feedboard 16, with cooperating pressure rollers 17 and 18 above them. A known "pusher device" not shown, preferably engages the rear edge of the sheet before it passes beyond the roller 14. The cylinders 11 and 12, as is usual, are arranged to be rotated, through suitable driving connections with other elements of the machine, by an electric motor 19 shown diagrammatically in Figure 4, and the sheet propelling rollers 14 and 15 are also suitably connected to the machine to be driven thereby in 45 timed relation with the cylinders 11 and 12 so that under normal operating conditions, sheets S2 will be continuously fed to the cylinders in proper timed relation with the printing plate on the cylinder 11.

50 A tripping mechanism, in this instance, including eccentric bearing sleeves 21 for supporting the bearings for the shaft ends of the impression cylinder 12 is provided, whereby the cylinder 12 may be "tripped" or separated from the plate cylinder 11. This mechanism for sep-

arating the impression cylinder 12 from the plate cylinder 11 into "trip off" position, further includes a link 22 connecting the bearing sleeves 21 to an arm 23 extending from a rock plate 24, having spaced apart pins 25 and 26 extending from a face thereof. The plate 24 when rocked into the position shown in Figure 1, actuates the bearing sleeves 21 to "trip on" or cause the cylinders 11 and 12 to engage the opposite sides of a sheet 51 being fed between them, and when rocked into the position shown in Figure 2, to "trip off" whereby the cylinders 11 and 12 are separated. A spring 27 is provided to hold the plate 24 in either "trip on" or "trip off" position.

The means for rocking the plate 24 includes a reciprocable trip bar 28 extending between the pins 25 and 26 and having a lug 29 extending outward from one side and a lug 31 extending outward from the other side. The arrangement is such that when the bar 28 is reciprocated, the lug 29 will engage the pin 25 to rock the plate 24 in one direction when the bar is raised into "up" position, and the lug 31 will engage the pin 26 to rock the plate in the other direction when the bar is in "down" position. The bar 28 is arranged to be reciprocated once during each revolution of the cylinders by means of a cam 32 rotatable with the cylinder 11 and acting through a roller 33 carried on an arm 34 of a lever pivoted at 35 to a stationary machine part, the other arm 36 of said lever being connected at 37 to one end of the bar 28. A spring 38 is provided to constantly bias the roller 33 toward and into engagement with the cam 32. The cam 32 is timed in relation to the rotation of the plate cylinder 11 so that the bar 28 will be reciprocated during the period that the usual gap between the ends of the printing plate on this cylinder is passing the bite between it and the impression cylinder 12.

Unless the bar 28 is raised from its position of "trip on," as shown in Figure 1, the cylinders will remain in printing relation, and therefore provision is included in this mechanism of means to raise the bar 28 to dispose the lug 29 thereon in position to engage the pin 25, on the plate 24, and rock this plate when the bar 28 is next reciprocated by the cam 32. For this purpose, the other end of the bar 28 is connected by a link 39 to an arm 40 of a trip lever 41, another arm 42 of which carries a roller 43 arranged to ride upon a cam 44, also rotatable with the plate cylinder 11. The cam 44 is timed to swing the trip lever 41 into the "down" position shown in Figure 1, whereby the cylinders will be tripped "on" and to swing the lever 41 into the "up" position shown in Figure 2, whereby the cylinders will be tripped "off," during the period the gap in the cylinder between the plate ends is passing the bite between the cylinders, and before the cam 32 acts to reciprocate the bar 28. A spring 45 is provided to bias the roller 43 toward the cam 44.

When the sheets are being fed in proper timed relation to the cylinders 11 and 12, there is no necessity for tripping "off" the cylinders, and therefore means in the form of a catch 46 is herein provided, to prevent the roller 43 from following the cam 44 and raising the bar 28 to "up" position, thereby lifting bar 28. The catch 46 is adapted to swing upon a stationary pivot pin 47 into a position shown in dotted lines in Figure 1, and will then be disposed in the path of a catch plate 48 secured to the lower end of the trip lever 41, and thus retain it in the position, shown in Figure 1, whereby the bar 28 will remain in "down" or trip "on" position, because the roller

43 will be held in the position shown in Figure 1, and prevented from swinging downward while the low portion of the cam 44 is passing. To insure that the cylinders will remain in tripped "on" position when the sheets are being fed in proper timed relation, the catch 46 is under the control of the front end of the advancing sheet 52 through a sheet detecting or trip control device. The trip control device shown includes a detector finger 49 mounted to swing freely on a pivot pin 51 and preferably counterweighted or otherwise arranged to be constantly urged into upstanding position, as in Figure 1, and against a stationary pin 53, to be disposed in the path of sheets being fed along the guides 13 by the rollers 14 and 15.

The finger 49, in this instance, is of light weight construction, and is secured to a lever 52 pivoted on the pin 51, and having a depending arm 53 to which a stop 54 is secured. The stop 54 extends into the path of movement of a reciprocable detector rod 55. The rod 55 is loosely supported in a stationary guide post 56 and is connected to the end of an arm 57 of a detector cam lever 58, pivoted at a mid-point on a stationary stud 59, and having a roller 61 upon its other arm adapted to ride on a detector cam 62 secured on a shaft 78 driven in timed relation with the printing cylinders. A spring 63 is provided to bias the roller 61 toward the cam 62.

The catch 46 is operatively connected to the detector cam lever 58 by a rod 64, one end of which is connected to an arm 65, extending from the catch 46 at the opposite side of the pivot pin 47. The other end of the rod 64 is connected to an arm 66 secured to the cam lever 58 and moving therewith. A pin 67 in the arm 66 extends through an elongated slot 68 provided in the rod 64. A spring 69 is secured at one end to the rod 64, and at its other end to the arm 66 and biases the upper end of the slot 68 toward the pin 67. The arrangement is such that the spring 69 acts to resiliently swing the catch 46 upwardly into the path of the end 48 of the lever 41, so it will snap into position to catch the lever 41 when this lever assumes the position shown in Figure 1, and when the detector cam lever 58 is caused to swing, due to the roller 61 riding down onto the low portion of the detector cam 62.

In order that the detector cam lever 58 may be swung to the position shown in dotted lines in Figure 1, when the roller 61 rides down onto the low portion of the detector cam 62 and cause the catch 46 to engage the trip lever end 48, the finger 49 must be swung downwardly by a sheet being fed along the guides 13, thereby swinging the arm 53 and moving the latch 54 out of the path of the adjacent end of the detector rod 55. Thus, if sheets are being fed along "in time," the finger 49 will be depressed in time to permit the catch 46 to engage the catch plate 48 on the trip lever 41 and restrain the roller 43 from riding down onto the low portion of the cam 44, which would raise the bar 28 into trip "off" position. From this, it follows that should a sheet be absent from the series of sheets being fed, the finger 49 will not be depressed and the catch 54 will then block the movement of the detector rod 55, and the roller 61 will be prevented from following down onto the low portion of the cam 62 and the catch 46 will thus be held in the position shown in full lines in Figure 1, allowing the roller 43 to ride down the cam 44 and raise the trip bar 28. The trip bar 28 being thus raised will, upon being reciprocated by means of the cam 32, rock the plate 24 to trip "off" the impression, and it re-

mains "off" while the cylinders rotate through the period that would otherwise be employed in printing the absent sheet. Obviously, the next sheet passing "in time" will again set the elements to trip the cylinders into "on" impression in readiness to receive and print upon this "in time" sheet. It will be observed that the upper side of the latch 54 is an inclined surface and when the rod 55 moves along it the finger 49 is drawn downward to such extent that it cannot touch the underside of a passing sheet.

In addition to means to trip "off" the impression when a sheet is absent from the series being fed, means are also herein provided to stop the machine and to set the mechanism to trip "off" the impression, when a sheet is moving along the feed table either ahead of time or behind time. The device to so control the tripping mechanism, is also controlled by the detector finger 49 and includes an electrical switch 71 having an operating button 72 extending beyond its casing, and positioned to be engaged by a rearwardly extending portion 91 of the finger 49. The switch 71 is carried at the end of an arm 73 of a cam lever 74, the other end 75 of which carries a roller 76 arranged to ride on a cam 77 rotatable with the cam 62 by being secured to the shaft 18. The lever 74 is pivoted upon a stationary stud 79 and a spring 80 is provided to bias the lever 74 to insure engagement of the roller 76 on the cam 77.

When the switch 11 is operated, it actuates electrical devices that serve to interrupt the current supply to the motor driving the machine and also to set the tripping control mechanism to "trip off" the printing cylinders. This trip setting action is effected by an electro-magnet 87 mounted on the machine frame and having an armature 88 held in alignment with the rod 64. When the magnet is energized, the armature moves into engagement with an end 89 of the rod 64 and prevents the rod being moved by the lever 66 to engage the catch 46 with the catch plate 48, and even if the rod 64 has been moved through operation of the hereinbefore described mechanical trip setting mechanism so as to engage the catch 46, if the magnet is energized, the resulting movement of the armature 88 will release the catch 46 and the "trip off" mechanism will function, because the slot 68 in the rod 64 permits movement of the rod by the electro-magnet even when the cam roller 61 is on a low portion of the cam 62.

The switch 71 as herein shown (Figure 4) is connected in a circuit extending from a line wire L1 through the switch 71, to a relay 81 and then to a line wire L2, whereby closing of the switch will energize the relay 81 and open a switch 82 controlled thereby. The switch 82 is in a circuit that extends from L2 through a switch 85 and a solenoid 84 to L1. This solenoid operates the switch 85 and also a motor switch 83. When the switch 82 is opened, it deenergizes the solenoid 84, opening the motor switch 83, and it will be understood that as is customary, an automatic brake is provided that will function to stop the machine quickly. Manual operation of a normally open push button switch 86 connected between the line wire L2 and the solenoid 84 will close a circuit paralleling the switches 82 and 85 and energize the solenoid 84 to close the motor switch 83 when it is desired to start the machine. The electromagnet 81, the function of which has hereinbefore been described, is connected in parallel with

the relay 81 and is energized when the switch 71 is closed.

The finger 49 is provided with a portion 91 extended to engage the switch button 72 (Figure 3) to operate the switch 71 if the finger 49 is depressed by a sheet at a time when the switch 71 is moved to the position shown in Figure 1. Under normal operating conditions, the switch 71 is moved away from the finger portion 91 by the cam 77 acting through the lever 74 when the roller 76 rides down to the low portion of the cam 77, and the button 72 does not close the switch, for this cam 77 is timed to cause the withdrawal of the switch just prior to the engagement of an "in time" sheet with the finger 49. Thus, in the case of sheets moving "in time," the circuit in which the switch 71 is connected will remain open, the motor 19 will continue in operation, and the electro-magnet 87 will not be energized.

From the foregoing description, it will be seen that should the sheet feeding mechanism fail to function properly and a sheet is misplaced and passing along the feed board later than at the proper time, the finger 49 will not be depressed in time to block the movement of the rod 55 and the mechanical tripping mechanism will function to trip "off" the impression of the printing cylinders, without stopping the machine; also should a sheet be misplaced and passing along the feed board in advance of the proper time, or should its passage be obstructed in some manner and it is delayed so that it holds the finger 49 down during a period when no sheet should be at that point, the switch 71 will be moved forward while the finger 49 is depressed by the sheet, and in consequence, the tripping mechanism will be set to "trip off," and the machine will be stopped. When the sheet has been removed, the machine can be restarted by manual operation of the push button 86.

It will be understood that the invention may be embodied in other specific forms without departing from the spirit or essential attributes thereof, and it is therefore desired that the present embodiment be considered in all respects as illustrative and not restrictive, reference being had to the claims rather than to the foregoing description to indicate the scope of the invention.

What I claim is:

55 1. In a sheet fed printing machine, sheet feeding means, and a cylinder tripping mechanism adapted to be set in "trip on" and "trip off" positions, control means for the tripping mechanism, including a sheet detector finger disposed in the path of travel of the sheets, to be engaged and displaced by each sheet and so held while the sheet is passing, to effect the setting of the tripping mechanism into "on" position
60 when the sheet engages and moves the finger in proper timed relation with cylinder rotation, and a second means actuated when the finger is held displaced by a sheet present at an improper time, to effect the setting of the tripping
65 mechanism to "off" position.

2. In a sheet fed printing machine, sheet feeding means, and cylinder tripping mechanism adapted to be set in "trip on" and "trip off" position, control means for the tripping mechanism, including a sheet detector finger disposed in the path of travel of the sheets, to be engaged and displaced by each sheet and so held while the sheet is passing to effect the setting of the tripping mechanism into "on" position when the sheet engages and moves the finger in proper

timed relation with cylinder rotation, and a second means actuated when the finger is held displaced by a sheet present at an improper time, to effect the setting of the tripping mechanism to "off" position and to stop the machine.

3. In a sheet fed printing machine having rotatable printing cylinders, and sheet feeding means, cylinder tripping mechanism adapted to be set in "trip on" and "trip off" positions, control means for the tripping mechanism including a sheet detector finger disposed in the path of the travel of the sheets, to be engaged and displaced by each sheet and so held while the sheet is passing to effect the setting of the tripping mechanism into "on" position when the sheet engages and moves the finger in proper timed relation with cylinder rotation, and a second means actuated when the finger is held displaced by a sheet present at an improper time, to stop the machine.

4. In a tripping mechanism for a sheet printing machine, the operation of which is dependent upon timed feeding of the sheets thereto for normal control of the mechanism, first and second trip devices, a swinging finger normally disposed in the path of the sheets being fed, to be engaged and swung thereby, a first member extending from the finger and swinging therewith to effect actuation of the first trip device when sheets are being fed "in time," and a second member extending from the finger and swinging therewith to effect actuation of the second trip device in a manner opposite to that effected by the first trip device when a sheet is fed at an improper time, and to stop the operation of the printing machine.

5. A control device for the cylinder tripping mechanism of a sheet printing machine driven by an electric motor, the device being dependent for normal control of the mechanism upon sheets being fed in timed relation thereto and including a swinging finger disposed in the path of the sheets being fed to the machine, a first member swinging with the finger and engageable with a mechanically operated control device to set the tripping mechanism in condition to trip the cylinders when a sheet is absent from the series being fed, and a second member swinging with the finger and engageable with an electrically operated control device to set the tripping mechanism in condition to trip the cylinders and to stop the machine driving motor when a sheet is being improperly fed.

6. A sheet fed printing machine having printing cylinders and sheet guides, a cylinder tripping mechanism having a sheet detector finger moved from a normal position to a second position when engaged by a sheet within a zone on the sheet guides, and a first trip controlling device actuated by the finger when it is so moved by a sheet that is within the zone at a proper time in relation to the rotation of the printing cylinders, in combination with a second trip controlling device actuated by the finger when a sheet is present within the zone at an improper time in relation to the rotation of the printing cylinders.

7. A sheet fed printing machine having printing cylinders and sheet guides, a cylinder tripping mechanism having a sheet detector finger moved from a normal position to a second position when engaged by a sheet within a zone on the sheet guides, and a mechanical trip controlling device actuated when the finger is moved to the second position by a sheet within the said

zone at a proper time in relation to the rotation of the printing cylinders, in combination with an electrically actuated trip controlling device energized when the finger is held in the second position by a sheet present within the zone at an improper time in relation to the rotation of the printing cylinders.

8. In a sheet fed printing machine having printing cylinders and a cylinder tripping mechanism having a latch, cam operated means to release the latch, electrically operated means to release the latch, and a sheet detector operable to control the cam operated means and the electrically operated means.

9. In a sheet fed printing machine having printing cylinders and a cylinder tripping mechanism having a latch, first cam operated means to release the latch, solenoid operated means to release the latch, a switch controlling the solenoid, second cam operated means to bodily move the switch, and a sheet detector operable to control the first cam operated means and to operate the switch.

10. In a rotary sheet fed printing machine, sheet feeding means, cylinder tripping mechanism adapted to be set in "trip on" and "trip off" positions, control means for the tripping mechanism, including a sheet detector finger disposed in the path of travel of the sheets, to be engaged and displaced by each sheet and so held while the sheet is passing, and means actuated by the finger, when in its displaced position to stop the printing machine.

11. In a rotary sheet fed printing machine, sheet feeding means, cylinder tripping mechanism adapted to be set in "trip on" and "trip off" positions, control means for the tripping mechanism, including a sheet detector finger disposed in the path of travel of the sheets, to be engaged and displaced by each sheet and so held while the sheet is passing, and means actuated by the finger, when in its displaced position, to effect the setting of the tripping mechanism into "off" position and to stop the machine.

12. In a tripping mechanism for a sheet printing machine dependent for normal operation upon timed feeding of sheets thereto, a pivotally supported finger normally disposed in the path of the sheets being fed and having first and second members swinging therewith, a first trip control device operated by a first one of the members and arranged to effect mechanical operation of the tripping mechanism, and a second trip control device operated by a second one of the members and arranged to effect electrical operation of the tripping mechanism.

13. In a tripping mechanism for a sheet printing machine driven by a motor, and its operation being dependent upon timed feeding of the sheets thereto for normal control of the mechanism, first and second trip devices, a swinging finger disposed in the path of the sheets being fed, to be engaged and swung by each sheet and so held while the sheet is passing, a first member associated with the finger to swing therewith and operate the first trip device to effect a mechanical actuation of the tripping mechanism, and a second member associated with the finger to swing therewith and operate the second trip device to effect electrical operation of the tripping mechanism.

14. In a tripping mechanism for a sheet printing machine driven by a motor, and its operation being dependent upon timed feeding of the sheets

thereto for normal control of the mechanism, first and second trip devices, a pivoted finger normally disposed in the path of the sheets being fed, to be engaged and swung by each sheet and so held while the sheet is passing, a first member swinging with the finger to operate the first trip device to effect a mechanical actuation of the trip-

ping mechanism, and a second member swinging with the finger to operate the second trip device to effect electrical operation of the tripping mechanism, and to stop the machine driving motor.

MORRIS S. GUDGER.
